DESIGN FOR A DISPENSING DEVICE

Edward H. Beardsley and Frederick A. Lobley,
Elkhart, Ind., assignors to Miles Laboratories,
Inc., Elkhart, Ind., a corporation of Indiana

Application June 6, 1947, Serial No. 139,490

Term of patent 14 years

(Cl. D52—2)

To all whom it may concern:

Be it known that we, Edward H. Beardsley and Frederick A. Lobley, citizens of the United States and residing at Elkhart, in the county of Elkhart and State of Indiana, have invented a new, original, and ornamental Design for a Dispensing Device, of which the following is a specification, reference being had to the accompanying drawing forming a part thereof. In the drawing:

Figure 1 is a side elevation of a dispensing device showing our new design, the dotted outline indicating a carton positioned therein for illustrative purposes only;

Figure 2 is a plan view of the dispensing device of Figure 1;

Figure 3 is a rear elevation of the dispensing device of Figure 1; and

Figure 4 is a front elevation of the dispensing device of Figure 1.

We claim:

The ornamental design for a dispensing device, substantially as shown and described.

EDWARD H. BEARDSLEY.
FREDERICK A. LOBLEY.
